US00D924831S

(12) **United States Design Patent** (10) **Patent No.:** **US D924,831 S**
(45) **Date of Patent:** **** Jul. 13, 2021**

(54) **DISPLAY DEVICE**

(71) Applicant: **SAMSUNG DISPLAY CO., LTD.**,
Yongin-si (KR)

(72) Inventors: **Hyun Joo Lee**, Cheongju-si (KR); **Eui Ri Cho**, Suwon-si (KR); **Ki Ho Lim**, Suwon-si (KR); **Seung-Gyun Woo**, Hwaseong-si (KR); **Jun Woo Kim**, Seoul (KR)

(73) Assignee: **Samsung Display Co., Ltd.**, Yongin-si (KR)

(**) Term: **15 Years**

(21) Appl. No.: **29/714,007**

(22) Filed: **Nov. 20, 2019**

(30) **Foreign Application Priority Data**

May 23, 2019 (KR) 30-2019-0024322
